COMBINATION TOOL CASE AND SAWHORSE

Robert B. Fray, Mission, Kans.

Application July 16, 1951, Serial No. 237,040

2 Claims. (Cl. 144—285)

1

This invention relates to equipment for use by carpenters and like artisans, and has for its primary object the provision of a tool chest or case that is quickly and easily convertible into a sawhorse and at the same time presenting the tools of the chest to the workmen for easy access.

It is another object of this invention to provide a portable assembly that includes a pair of hingedly interconnected, tool-receiving panels, each of which includes parts that cooperate when the panels are swung in one direction to enclose a plurality of tools and operable when the panels are swung in the opposite direction away from each other in connection with releasable holding means therefor to present a strong, rigid sawhorse or working bar.

Another object of the present invention is to provide a sectional tool case that includes a pair of substantially identical, relatively shallow sections presenting a closed body when the sections are in edge-to-edge engagement, one end wall for the body being common to the sections and presenting a working surface or uppermost apex edge for a sawhorse when the sections are separated and moved to the open condition.

Other objects include the way in which releasable end plates are provided for joining the sections of the case when the same are swung to an open condition operable as supporting legs for the sawhorse; the manner in which a pair of opposed hinges are provided on the sections for joining the same with the aforesaid common end wall; the manner in which a relatively large number of tools may be mounted within the case; and many more minor objects, all of which will become clear as the following specification progresses, reference being had to the accompanying drawing, wherein:

Figure 1 is a perspective view of a combination tool case and sawhorse illustrating its position when used as a sawhorse.

Fig. 2 is a vertical, substantially central, cross-sectional view illustrating the case in a closed condition.

Fig. 3 is an elevational view of the innermost face of one of the case sections showing some of the tools mounted therein; and

Fig. 4 is an enlarged, detailed, cross-sectional view showing one of the releasable fastening elements for the end plates of the sawhorse.

The combined assembly of the present invention embodies a shallow, tool-receiving case broadly designated by the numeral 10 shown in the closed condition in Fig. 2 of the drawing and

in the open condition by Fig. 1, adapting the same for use as a sawhorse.

Case 10 includes a pair of substantially identical sections 12 and 14, each of which in turn consists of a fiat, polygonal panel 16, a pair of elongated, relatively narrow, opposed side walls 18 and a single, elongated, relatively narrow end wall 20 joining the side walls 18 at one end thereof. The two side walls 18, as well as the end wall 20, are secured rigidly to the corresponding panel 16 and such reinforcement as L-shaped brackets 22 may be provided on the innermost faces of walls 18 and 20 and panels 16 as may be desired.

15 The sections 12 and 14 are provided with a common end wall opposite to the walls 20 that comprises an elongated member or bar 24 having a hole 25, presenting a handle. The thickness of the member 24 is preferably greater than that of either of the panels 16 or the side and end walls 18 and 20 and as illustrated in Fig. 2 of the drawing, the width of the elongated member 24 is twice that of the two end walls 20. The length of the member 24 is preferably substantially the

25 same as the distance between the outermost faces of side walls 18. Each panel 16 extends as at 26 at that end thereof opposite to end wall 20 slightly beyond the proximal ends of side walls 18, and an elongated hinge 28 connected with 30 such extension 26 and with a corresponding longitudinal edge of the member 24, swingably secures the panels 16 to the member 24. In other words, there is provided a pair of hinges 28 for connecting the member 24 to the sections 12 and 14 in opposed relationship to the end walls 20.

It is seen that the extensions 26 are coextensive in length with the member 24 and are of substantially the same width as the thickness of the member 24. Accordingly, when the sections 12 40 and 14 are swung toward each other in one direction to the condition illustrated in Fig. 2 of the drawing, all of the side walls 18, as well as the two end walls 20, are in abutting interengagement and the extensions 26 are in overlapping 45 relationship to the longitudinal edges of the member 24, thereby presenting a completely closed tool-receiving chest or case.

In order to adapt the hollow body 10 for use as a sawhorse or work table in a manner illustrated by Fig. 1 of the drawing, the sections 12 and 14 are swung on the member 24 by means of hinges 28, away from the position shown by Fig. 2 of the drawing with the sections 12 and 14 diverging downwardly from the member 24.

55 In order to hold the sections 12 and 14 against

movement toward and away from each other while the unit is used as a sawhorse, there is provided a pair of flat plates 30 releasably secured to the side walls 18 of the sections 12 and 14.

One type of releasable fastening element is illustrated in detail by Fig. 4 of the drawing and designated broadly by the numeral 32. Element 32 is carried by the plate 30 through the medium of an opening 34 in the latter and held in place by a small bolt or the like 36. A pair of semi-spherical, resilient elements 38, forming a part of the fastener 32, is wedged into a cavity 40 formed in the corresponding side wall 18, the elements 38 being normally biased apart when the plates 30 are stored within the body 10 as illustrated with respect to one of such plates 30 in Fig. 1 of the drawing.

Suitable opposed guides 42 within one of the sections 12-14 serve to receive the plates 32 when the same are not in use to support the sections 12 and 14 in the manner shown by Fig. 1 of the drawing.

Suitable arrangement may be provided within the sections 12 and 14 and particularly on the panels 16 thereof to receive various types of tools including hammers, screwdrivers, saws, and the like. Such structure is illustrated in part by Figs. 2 and 3 of the drawing, but since the same form no particular part of the present invention, it need not be further described. It can well be appreciated that the panels 16 are capable of receiving a relatively large number of tools and that when the sections 12 and 14 are swung to the condition shown by Fig. 1 of the drawing, all of these tools will be in full view and readily accessible to the workman. By providing means for mounting of the tools on the panels 16, the unit may be used as a sawhorse or the like without the necessity of first removing all of the tools from the body 10 prior to opening the same and conditioning the unit for use as a sawhorse.

Having thus described the invention what is claimed as new and desired to be secured by Letters Patent is:

1. A combination tool case and sawhorse com-

prising a pair of complementary, shallow, tool-receiving case sections adapted for disposition in edge-to-edge interengagement; an elongated member common to the sections and forming one end wall thereof, said member having an inner and an outer flat surface when the case sections are closed; hinge means for each section respectively and joining the same to said member; and releasable means joining the sections for holding the same in a position diverging downwardly from said member when the sections are swung apart on said hinge means away from said edge-to-edge interengagement and when said inner surface of the member faces upwardly.

2. A combination tool case and sawhorse comprising a hollow body having a pair of opposed panels, each panel being provided with a pair of spaced side walls and one end wall joining the side walls; an elongated member between the panels; hinge means mounted on each longitudinal edge respectively of the member and joined with corresponding panels, said member presenting a second end wall closing the body when the panels are swung thereon to a position with their side walls and the one end wall thereof in edge-to-edge abutment, said member having an inner and an outer flat surface when the panels are in said position; and a plate having releasable means of attachment to one side wall of each panel respectively when the panels are swung away from said position to hold the panels in a position diverging downwardly from the member with said inner surface of the member facing upwardly.
